CLAIM

The ornamental design for a makeup tool, as shown and described.

DESCRIPTION

FIG. 1 is a perspective view of an embodiment of a makeup tool.

FIG. 2 is a front elevational view of FIG. 1.

FIG. 3 is a rear elevational view of FIG. 1.

FIG. 4 is a left side elevational view of FIG. 1.

FIG. 5 is a right side elevational view of FIG. 1.

FIG. 6 is a top plan view of FIG. 1; and,

FIG. 7 is a bottom plan view of FIG. 1.

While the accompanying drawings illustrate one or more example embodiments, it should be understood that according to other example embodiments that should be considered to be within the scope of the present disclosure, it is contemplated that any illustrated solid lines (or portions thereof) can be converted to broken lines and that any illustrated broken lines (or portions thereof) can be converted to solid lines to claim or disclaim portions, components, or sub-components of the designs shown. It is further contemplated that shading can be added or removed to claim or disclaim the corresponding surfaces.
